PHOTOELECTRIC SYSTEM FOR MULTIPLYING AND TRANSLATING ELECTRICAL IMPULSES

Bernard Kwartin, Brooklyn, N. Y.

Application March 14, 1931, Serial No. 522,760

2 Claims. (Cl. 179—100.3)

The present invention relates to the translation and recordation of sound and light effects and more particularly to an improved apparatus or system wherein photo-electric means is employed not only to translate sound and light effects emanating from an original source or from a photographic record thereof into corresponding electrical impulses but also to multiply the impulses so obtained.

10 In connection with the electrical translation of sound and light effects, many serious difficulties have been encountered in the various attempts to faithfully reproduce these effects, particularly in those instances when it is attempted 15 to materially amplify the electrical impulses or current variations which correspond to the sound or light effects as originally produced or as originally recorded. It is well known, for example, that when sounds to be transmitted are amplified 20 to an exaggerated extent they are so distorted in reproduction as to be practically unrecognizable. It is also well known that exaggerated amplification of the sounds not only prohibits the faithful reproduction of the very delicate overtones which give character and quality to speech 25 and musical sounds but also renders it practically impossible to clearly and distinctly define the nuances between sounds of strongest and weakest character. On the other hand, those 30 familiar with the art of electrically reproducing sound and light effects and with the art of electrically transmitting the same, realize that the most faithful reproduction thereof is obtained with a minimum amount of amplification. However, this minimum amplification is usually insufficient to insure the transmission or reproduction 35 of sounds in sufficient volume, as where the sounds are intended to be heard by a large audience spread over an extensive area.

40 It is among the principal objects of the present invention to provide an apparatus for and system or method of transmitting sound or light effects whereby a maximum volume of these effects is obtained in the reproduction thereof with 45 a minimum amplification of the current variations which are established in accordance with these effects as originally produced.

Still another object of the present invention is the provision of a photo-electric system of transmitting sounds whereby sound or light effects as originally produced may be simultaneously transmitted to and reproduced at points remote from one another, the corresponding electrical impulses received at the several points being separately and individually amplified as desired and

in such manner that the amplification had at one point exerts no influence whatsoever upon the impulses received at any other point.

Still another object of the present invention is the provision of a system for transmitting sound which is admirably suited for public addresses and the like and wherein a plurality of sound reproducing instruments derive their energy from a single source and wherein the number of the instruments so employed may be considerably increased without necessitating a corresponding increase in the energy supplied from said source.

Still another object of the invention is to provide a system or method of increasing the volume of transmitted electrical impulses wherein 15 is employed a single light source the intensity of which varies in accordance with the impulses as originally produced in combination with a plurality of photo-electric cells which are arranged to be individually but simultaneously influenced by the variable light source for respectively actuating a plurality of electrically operated devices, the value of the energy supplied to each of said devices being adjustable as conditions warrant independently of the value of the 20 energy supplied to any of the other loud devices and independently of the value of the current flowing in the circuit in which the light source is included.

Still another and important object of the present invention is the provision of a system or method of simultaneously producing a plurality of photographic records of sounds as originally produced wherein a single variable light source is employed for variably energizing as many different auxiliary light sources as there are records to be produced, the system being of such character that the energy received by one of said auxiliary light sources is entirely unaffected by any variations in energy supplied to any of the 40 other auxiliary light sources.

From the foregoing, it will be observed that in general the object of the present invention is to provide a single source of variable energy which is capable of energizing a plurality of electrically operated devices, the energy of the said single source being neither diminished nor increased nor otherwise affected by the increase or decrease in the number of devices employed.

Other objects of the invention will appear more fully hereinafter.

The invention consists substantially in the combination, construction, location and relative arrangement of parts and in the method of using the same, all as will appear more fully herein- 55

after, as shown in the accompanying drawings, and as finally pointed out in the appended claims.

In the said accompanying drawings wherein I showed preferred arrangements embodying the 5 principles of this invention and which drawings are intended solely for illustrative purposes:—

Figure 1 is a more or less diagrammatic view showing one form of arrangement for carrying out the principles of the present invention and 10 wherein the sounds as received by a microphone are reproduced by a plurality of loud speakers;

Figure 2 is a similar view wherein the sounds reproduced by a plurality of loud speakers emanate from a photographic film record thereof; 15 and

Figure 3 is a diagrammatic view showing an arrangement wherein the invention is employed to obtain a plurality of photographic master film records of sounds as originally produced and 20 received by a single microphone.

Referring now to the drawings and more particularly to Figure 1 thereof, it will be observed that the sounds which are to be transmitted or reproduced are initially received by a suitable 25 microphone 10 or similar device which is adapted to convert the sound vibrations as originally produced into corresponding electrical current variations. These current variations which are thus set up in the microphone circuit 11 are employed 30 to energize an actinic lamp 12 or other source of light capable of producing light rays of varying intensity. It will be understood, of course, that the intensity of the light rays which emanate from the primary source of light 12 is entirely 35 dependent upon and is in accordance with the current variations established in the microphone circuit 11.

If desired, the current variations established in the microphone circuit 11 may be suitably amplified 40 preliminarily to energizing the lamp 12. Suitably arranged to be influenced by the light variations emanating from the primary lamp 12 are a plurality of photo-electric cells 13. These photo-electric cells 13 are preferably positioned 45 with respect to the primary source of light such that each of them is similarly influenced to establish similar current fluctuations in the photo-electric cell circuits 14. Inasmuch as the light rays which emanate from the light source 12 are 50 of the same intensity in all directions, it is obvious that as many photo-electric cells 13 may be employed as can be conveniently positioned symmetrically about the source of light. Each of the photo-electric cells 13 is included in any suitable type of amplifying circuit 15 for supplying a 55 variable current to the respective sound reproducing devices, such as the loud speakers 16. It will be understood that a separate loud speaker 16 is employed for each photo-electric cell 13 and that the number of loud speakers employed is 60 dependent solely upon the number of photo-electric cells which can be conveniently positioned symmetrically with respect to the light source 12. It will thus be seen that by increasing the 65 number of photo-electric cells 13 and their associated loud speakers the volume of the transmitted sounds may be increased very considerably without, however, necessitating any change whatsoever in the energy originally supplied to 70 the light source 12. By virtue of the arrangement shown in Figure 1, even the feeblest sound received by the microphone 10 is converted into a corresponding light variation which is sufficient to immediately and simultaneously influence all 75 of the photo-electric cells whereby there is pro-

duced a multiplied volume of sounds. Due to the fact that the current variations established in the microphone circuit 11 are not amplified to an exaggerated extent, the sound as produced by the loud speaker 16, although very markedly increased in volume, are not distorted and are faithful reproductions of the sounds as originally produced. If desired, and in some instances it may be preferable to do so, suitable means may be introduced in the several photo-electric cell circuits or in the several loud speaker circuits, to control the volume of sounds produced by each loud speaker independently of the volume produced by the other loud speaker. This may be of great advantage in those cases where a public 15 address is being received by audiences situated in different rooms or in different buildings the sizes of which vary and in consequence of which it would be desirable to diminish or increase the volume of the sound received by any one audience. 20

Figure 2 shows the application of the present invention to the transmission of sounds which have been recorded upon a photographic film 17. In such an arrangement the film 17 travels past a constant source of light 18. The light rays emanating from the lamp 18 pass through the photographic film record and are received by a photo-electric cell 19. This photo-electric cell 19 is thus influenced to establish varying current fluctuations in the photo-electric cell circuit 20 which 30 may be amplified, as at 21, preliminarily to variably energizing a primary source of light 22. This primary source of light 22 is in all respects similar to the actinic lamp 12 of Figure 1 and is surrounded by a plurality of symmetrically positioned photo-electric cells 23. As in the former arrangement, each of these photo-electric cells 23 35 is in electrical circuit with and is adapted to actuate a loud speaker 24. With the exception of the source of sound, the arrangement of Figure 2 is 40 similar in all respects with that of Figure 1.

Figure 3 illustrates the application of the present invention to the production of a plurality of photographic master film records 25 of sounds 45 as originally produced. As in the former instance, the sounds as originally produced are received by a microphone 26 by which the sounds are converted into corresponding electrical current variations. These latter variations variably energize a variable source of light 27 whereby to 50 produce light rays of varying intensity for influencing the photo-electric cells 28. Each of these photo-electric cells converts the light rays into corresponding electrical current variations, these latter in turn being employed to energize 55 secondary light sources 29. These secondary light sources 29 are each in the form of an actinic lamp or its equivalent and are each capable of producing light rays of varying intensity in accordance with the current variations established 60 in its respective photo-electric cell circuit. As many photographic film records can thus be obtained as there are photo-electric cells 28 grouped about the single primary source of light 27. As 65 in the arrangements previously described, the energy supplied to any one of the secondary actinic lamps 29 does not affect the energy supplied to the remaining actinic lamp 29 and inasmuch as each of the latter is similarly energized a plurality of photographic film records is obtained 70 at one and the same time. Each of these records so obtained may be used as a master record of the sounds received by the single microphone 26.

While in the foregoing specification the invention has been described more particularly in its 75

application to the transmission, recordation and reproduction of sounds and sound effects, it will be understood that the same is equally applicable for translating and multiplying light and other effects which are capable of being converted into corresponding electrical impulses such as are employed in connection with telephotography, television and the like.

It will be understood of course that various changes may be made from time to time in the arrangement and in the methods herein shown and described without departing from the real spirit or general principles of the invention, and it is accordingly intended to claim the same broadly, as well as specifically, as indicated in the appended claims.

What is claimed as new and useful:—

1. In a sound translating system, in combination, means for establishing electrical current variations in accordance with the sounds to be reproduced, means energizable by said current variations for producing light rays the intensities of which vary in accordance with said originally produced current variations, a plurality of photo-electric elements located with respect to said

light producing means as to be uniformly influenced thereby, and a plurality of electrically operated sound reproducing devices respectively associated with each of said photo-electric elements for independently reproducing the sounds simultaneously and at differently located points. 5

2. In a system for producing simultaneously a plurality of similar records of sounds as originally produced, in combination, means for receiving said sounds and converting the same into corresponding electrical current variations, a light producing element energizable by said current variations to produce variable light rays, a plurality of light sensitive devices adapted to be independently but similarly influenced by said variable light rays whereby to establish a plurality of independent current variations which are respectively in accordance with the originally produced sound vibrations, and a plurality of variable light producing elements respectively associated with each of said devices for producing a corresponding number of similar records of the sounds. 15 20
